Geo. P. Kimmel.

ATTORNEY.

UNITED STATES PATENT OFFICE.

HOMER G. COY, OF NEW YORK, N. Y.

AUTOMATIC ERASER.

Application filed January 18, 1927. Serial No. 161,899.

This invention relates to erasers, more particularly to an eraser of the power operated type, and has for its object to provide, in a manner as hereinafter set forth, a device of the type referred to including an erasing or abrading element capable of having a vibratory action imparted to a portion thereof to provide an erasive action to quickly and efficiently remove ink or pencil lines or ink or pencil markings or other markings to be erased.

Further objects of the invention are to provide, in a manner as hereinafter set forth, an eraser which is simple in its construction and arrangement, strong, compact, durable, thoroughly efficient in its use, conveniently thrown into active position, readily assembled, and comparatively inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a front elevation of an eraser, in accordance with this invention, in inactive position and mounted upon a support.

Figure 2 is a fragmentary view in longitudinal section illustrating the erasing or abrading element carrier.

Figure 3 is a section on line 3—3 Figure 2.

Figure 4 is a section on line 4—4 Figure 2.

An eraser, in accordance with this invention includes a vibratory erasing or abrading element, a manually portable carrier or holder therefor, and an electrically operated combined fluid pressure supply and suction mechanism to provide for the vibration of the erasing or abrading element to set up an erasing function for the latter.

The carrier or holder for the erasing or abrading element consists of a body portion 1, of appropriate length so that it can be grasped by the hand and held or shifted to the desired position and preferably the body

portion 1 is of circular cross section. The body portion 1 at its lower or inner end is 55 of tapered contour as indicated at 2. The body portion 1 is formed with a lengthwise extending centrally disposed bore 3 which corresponds in contour to the shape of the erasing or abrading element 4, which is adjustably mounted in position and permanently set to project a substantial distance from the lower end of the body portion 1. The abrading element 4 is constructed of any suitable material, such as rubber possessing a characteristic to set up an abrasive or erasive action when the device is used. The bore 3 extends from one end to the other end of the body portion 1 and has its inner or lower portion enlarged, as at 5. 60 The enlarged inner terminal portion 5 of the bore 3 projects laterally in one direction, with respect to the remaining portion of the bore 3, and is disposed diametrically of the carrier or holder. The portion 5 of the bore 3 provides a clearance to permit of the inner or lower terminal portion 6, of the element 4, to vibrate. The upper or outer end of said body portion 1, is provided with a nipple 7 which forms a continuation of a channel 8 extending lengthwise of the body portion 1.

The channel 8 is a combined fluid pressure supply and suction passage and at its inner end terminates in the outer end of a 85 port 9 disposed diametrically of the body portion 1. The inner end of the port 9 is normally closed by the inner or lower terminal portion 6 of the element 4. The inner end of the port 9 is adapted to communicate 90 with the enlarged inner or lower terminal portion 5, of the bore 3, at a point removed from the lower or inner end of the body portion 1.

The element 4 is adjustably mounted in 95 the body portion 1, to enable it to be adjusted to extend the desired distance from the inner or lower end of the body portion 1 as the inner or lower end thereof wears away. The element 4 is secured in adjusted positions by a diametrically disposed set screw 10 having threaded engagement with the body portion 1, and with its inner end abutting against element 4 to clamp it in adjusted position against the wall of the bore 105 3. Attached to the body portion 1 is a

bail 11 for hanging the carrier or holder up and further for normally maintaining a spring controlled circuit closer, to be presently referred to, in inactive position.

5 The electrically operated mechanism to provide a vibratory action to the inner or lower projecting end of the element 4 includes a flexible, combined fluid pressure supply and suction pipe 12 which is connected to the nipple 7. The said mechanism further includes a pump 13 mounted within a casing 14 and operated from an electric motor 15 which is also arranged in the casing 14. The pump 13 includes a cylinder 16 having an air supply port 17 intermediate its ends and a combined air discharge and suction port 18 at its lower end. The cylinder 16 forms a piston chamber 19 in which operates a piston 20 to provide for 10 alternate fluid pressure supply and suction steps with respect to the inner or lower terminal portion 5, of the element 4 thereby causing said terminal portion to vibrate, on the operation of the pump, to set up the 15 erasing or abrading function for the element 4. The pipe 12 is connected to the casing 14 and opens into the port 18.

The position of the port 17, in the cylinder 20, is such that the port 17 will be cleared by the piston at the limit of the up-stroke of the piston, the latter then descends past the port 17 and forces the air beneath it through the port 18, pipe 12, channel 8 and port 9 against the inner or lower terminal portion 5, of the element 4, causing it to move away from the inner end of port 9. The piston then rises and creates a suction action back through port 9, channel 8, pipe 12 and port 18. This back suction, together with the resiliency of element 4, causes the inner or lower terminal portion 5 of the latter, to move back to its original position closing the inner end of port 9. The piston continues to rise until it clears port 17, which again admits air to the piston chamber beneath the piston and the descending operation of the piston is repeated. In Figure 1, the piston is shown in full lines, just before it reaches the limit of its up-stroke and in dotted lines just before it reaches the limit of its downstroke.

The circuit connections for the motor 15, are indicated at 21 and which includes a contact 22 and a spring controlled circuit closer 23, normally maintained clear of the contact 22, by the hanging of the carrier or holder 1 on the closer 23. When the carrier or holder is removed from the circuit closer 23, the controlling spring of the latter will swing it to engage with the contact 22 thereby closing the motor circuit. The driving connection between the motor 15 and the piston 20, is indicated at 24. The casing 14 has a door 14'.

65 The pipe 12 is of an appropriate length,

so that the carrier or holder can be shifted to any point desired. On the operation of the pump it will provide for a vibratory movement at the inner or lower terminal portion 6 of the element 4, so the said element 4 will perform its erasing or abrading action.

It is thought the many advantages of an eraser, in accordance with this invention, can be readily understood, and although the preferred embodiment of the invention is as illustrated and described, yet it is to be understood that changes in the details of construction can be had which will fall within the scope of the invention as claimed.

What I claim is:-

1. An eraser comprising an erasing element carrier including means to provide for the alternate application of fluid pressure and suction directly upon a terminal portion of said element to vibrate such portion, and a pumping element having an air intake and further having a combined air discharge and suction port communicating with said means.

2. An eraser comprising a manually portable erasing element carrier including means to provide for the alternate application of fluid pressure and suction directly upon an end terminal portion of said element to vibrate such portion, a pumping mechanism having an air intake and a combined air discharge and suction port communicating with said means, and an electric motor normally in an open circuit, said motor operatively connected with said pumping mechanism and operating the same when the motor circuit is closed.

3. An eraser comprising an adjustable erasing element, a portable carrier therefor, said carrier including means to provide for the alternate application of fluid pressure and suction directly upon an end terminal portion of said element to vibrate such portion, and a pumping element having an air intake and a combined air discharge and suction port communicating with said means, said carrier further including means for maintaining the erasing element in adjusted positions.

4. An eraser, comprising in combination a carrier provided with a combined fluid pressure supply and suction channel and a bore communicating intermediate its ends with said channel, said bore opening at the ends of the carrier, an erasing element mounted in said bore, extending through and projecting from the carrier and normally closing the bore to said channel, said bore having an enlarged terminal portion to permit of the vibration of that part of said element projecting from the carrier, and a pumping device having an air intake and a combined air discharge and suction port communicating with said channel to cause

an alternate application of fluid pressure and suction directly upon that portion of said eraser element extended from the carrier to vibrate such portion.

5. An eraser constructed in accordance with claim 4, said pumping device including a flexible pipe interposed between and opening into said port and channel.
6. An eraser constructed in accordance with

claim 4, an electric motor normally in an open circuit and having an operative drive connection with said pumping device for operating the latter when the motor circuit is closed.

In testimony whereof, I affix my signature hereto.

HOMER G. COY.
